US0D1104954S

(12) **United States Design Patent** (10) **Patent No.:** **US D1,104,954 S**
(45) **Date of Patent:** **** Dec. 9, 2025**

(54) **AUDIO ADAPTER FOR CHARGING**

(71) Applicant: **Luxshare Precision Industry(Chuzhou), Ltd.**, Chuzhou (CN)

(72) Inventors: **Yujie Xie**, Chuzhou (CN); **Shun Wang**, Chuzhou (CN); **Changming Du**, Chuzhou (CN); **Huaizhou Liu**, Chuzhou (CN)

(73) Assignee: **LUXSHARE PRECISION INDUSTRY (CHUZHOU), LTD.**, Chuzhou (CN)

(**) Term: **15 Years**

(21) Appl. No.: **29/895,437**

(22) Filed: **Jun. 21, 2023**

(30) **Foreign Application Priority Data**

Dec. 28, 2022 (CN) 202230868248.5

(51) **LOC (15) Cl.** **13-02**

(57) **CLAIM**

The ornamental design for an audio adapter for charging, as shown and described.

DESCRIPTION

FIG. 1 is a first perspective view of the audio adapter for charging showing our new design;

FIG. 2 is a second perspective view of the audio adapter for charging;

FIG. 3 is a third perspective view of the audio adapter for charging;

FIG. 4 is a fourth perspective view of the audio adapter for charging;

FIG. 5 is a fifth perspective view of the audio adapter for charging;

FIG. 6 is a sixth perspective view of the audio adapter for charging;

FIG. 7 is a seventh perspective view of the audio adapter for charging;

FIG. 8 is a eighth perspective view of the audio adapter for charging;

FIG. 9 is a front plan view of the audio adapter for charging;

FIG. 10 is a rear plan view of the audio adapter for charging;

FIG. 11 is a left plan view of the audio adapter for charging;

FIG. 12 is a right plan view of the audio adapter for charging;

FIG. 13 is a top plan view of the audio adapter for charging;

FIG. 14 is a bottom view the audio adapter for charging; and,

(Continued)

FIG. 15 is a perspective view of the audio adapter for charging for supporting a mobile phone in an environment of use.

The broken lines depict portions of the audio adapter for charging that form no part of the claimed design. The additional broken lines showing a mobile phone in FIG. 15 depict environment that form no part of the claimed design.

1 Claim, 15 Drawing Sheets
